UNITED STATES PATENT OFFICE.

THOMAS A. ARNOLD, OF CAMBRIDGE, NEW YORK.

BOX FASTENER.

Application filed October 13, 1921. Serial No. 507,511.

To all whom it may concern:

Be it known that I, THOMAS A. ARNOLD, a citizen of the United States, residing at Cambridge, in the county of Washington 5 and State of New York, have invented certain new and useful Improvements in Box Fasteners, of which the following is a specification.

This invention relates to locking devices especially intended for securing the top or hinged lid of a box or crate, although it may be applied to other uses. The object of the invention is to provide a fastening device which may be attached to the top edge of a 15 box with a single nail or screw upon which the device may pivot and when the cover is applied the fastening device may be swung to embrace its edge and be secured by a single nail or screw.

20 In the following detailed description, I shall refer to the accompanying drawings in which—Figure 1 is a perspective view of a box or crate having the cover secured by means of my fastening devices; Fig. 2 is a 25 fragmentary perspective view showing the fastener swung outwardly to permit the cover or lid to be closed; Fig. 3 is a fragmentary top plan view of a box cover with the fastener in locked position; and Fig. 4 30 is a side elevation of the same.

The fastening device is formed of sheet metal stamped or pressed into a channel-shaped member 5, and having the bottom or base portion projecting from one end to form 35 a flange 6, which is perforated to receive a screw 7, by which it is pivotally secured to the top edge of the box.

The top and bottom flanges of the channel member 5 are spaced apart a distance 40 sufficient to permit the device to slide over the edge of the box cover, preferably with rather a close fit. One or more of the fastening devices are attached to opposite edges of the box or crate. When the cover consists 45 of two hinged portions as illustrated at 8 and 9 in Fig. 1, the fasteners are placed in alinement with the meeting edges of the

covers so that they will extend across the joint and overlap both cover members, in the manner shown.

50 The manner of using my box fastener will be apparent from the illustrations. The fastening devices 5 are swung outwardly upon their pivot screws 7 until they are perpendicular to the sides of the box or crate, 55 as shown in Fig. 2. The lid or cover members are then positioned on the box and the fastening devices are swung around parallel with the edge of the box so that the edge of the cover fits into the channel, the flanges 60 overlapping the upper and lower faces of the cover. By inserting a single nail or screw 10 through a hole 12 in the upper flange of each device, the cover will be securely locked. The end 5^a is cut under at an oblique angle 65 to form an overhanging portion to thereby permit the use of a long nail or screw 10 which will extend below the fastening device and penetrate the side of the box if desired. It will be observed that the side walls of 70 the fastening devices brace the cover against lateral thrusts while the top and bottom flanges clamp the cover securely to the edge of the box.

75 The advantages derived from the use of my box fastener will be appreciated especially by those who ship goods in crates or containers which are to be returned. The lids or covers are not marred or injured by the fasteners, while the closing and opening 80 operations are reduced to a minimum.

I claim:

A fastening device for boxes or containers, comprising a channel-shaped member having the lower base flange extended at one 85 end to form an attaching means, the end of said member opposite from the attaching end being under-cut to form an overhanging portion, said flange and said overhanging portion being provided with perforations to 90 receive suitable locking means.

In testimony whereof I affix my signature.

THOMAS A. ARNOLD.
